PRESSURE REGULATOR

James H. Rice, Chicago, and John W. Baur, Glenview, Ill., assignors to Binks Manufacturing Corporation, Chicago, Ill., a corporation of Delaware

Application November 5, 1954, Serial No. 467,173

3 Claims. (Cl. 137—505.47)

This invention relates to improvements in a flow regulator and refers particularly to a regulator for controlling the flow of a fluid which may carry suspended abrasive material.

In controlling the flow of fluid which carries suspended abrasive material, such, for instance, as finely divided ceramic material, metal valves or other metallic control devices are quickly rendered useless by virtue of the abrasive action of the flowing material.

The present invention is directed to a flow control device wherein the flow control agent may be constructed of a material, such as, flexible, resilient rubber or the like, which has high resistance to abrasion.

Accordingly, one of the features of the present invention resides in a flow control device which has an exceedingly long, useful life under the adverse conditions encountered in controlling the flow of an abrasive material.

Another important feature of the invention resides in a flow control mechanism which can maintain an accurate flow of abrasive material over a relatively wide range of rates of flow.

A further important feature of the invention resides in a flow control device which is simple in its operation and is most economical in construction.

Other objects and advantages of the present invention will be apparent from the accompanying drawing and following detailed description.

In the drawing,

Fig. 1 is a sectional elevational view of a device embodying the concepts of the present invention.

Fig. 2 is a top plan view of the device shown in Fig. 1 with the bonnet removed.

Fig. 3 is a detailed sectional view taken on line 3—3 of Fig. 1.

Referring in detail to the drawing, the device comprising the present invention comprises essentially a body portion 1, a bonnet 2 secured to the upper portion of the body by means of screws 3, and a bottom plate 4 secured to the lower portion of the body by screws 5. The side wall of the body carries an apertured inlet boss 6 and a spaced apertured outlet boss 7, said bosses preferably being formed integral with the wall of the body.

The body portion 1 is substantially hollow and is inferiorly divided by a web or partition 8 which is also preferably formed integral with the wall of the body. A groove 9 of substantially spiral configuration is provided in the upper face of the web 8, one end of said groove leading to the inlet boss 6 through passageway 10 and the other end of the groove leading to the outlet boss through passageway 11, said passageways being provided in the material comprising the web 8 and the wall of the body.

A flexible conduit 12 is positioned in said spiral groove 9 and the ends thereof extend into the inlet and outlet bosses 6 and 7, respectively. An externally threaded fitting 13 threadedly engages in the inlet boss 6 and a

2

similar fitting 14 engages in the outlet boss 7. By means of fittings 13 and 14, the device may be connected to a desired piping circuit through which the flow of fluid is to be controlled. A bushing 15 is positioned in the inlet boss 6 and when fitting 13 is tightened, frictionally grips the end of the tube 12. A similar bushing 16 is positioned in the outlet boss 7 which anchors and seals the opposite end of tube 12 when the fitting 14 is tightened.

10 A control plate 17 is positioned within the bonnet 2 and is adapted to rest upon the upper portion of the spirally coiled tubing 12 which is carried in the groove 9. The web or partition 8 carries a central boss 18 in which an aperture 19 is provided. A connecting rod 20 is slidably positioned in the aperture 19, said rod being secured at its upper end to the central portion of the plate 17 by means of nut 21.

A coil spring 22 abuts at one end upon the upper portion of plate 17 and at its opposite end said coil spring 20 abuts against a shouldered disc 23. The upper portion of the bonnet 2 is provided with a threaded aperture in which an adjusting screw 24 is positioned, said adjusting screw at its upper portion having a handle 25 whereby the screw may be conveniently rotated. The lower end of the screw 24 engages in a recess 26 provided in the upper face of the disc 23. The arrangement is such that by the manipulation of the screw 24 spring 22 may be relatively compressed or relatively released and hence control plate 17 will bear against the tubing 12 in a controlled manner.

The web or partition 8 adjacent the wall of the body 1 is provided with a valve chamber 27 in which a valve gate 28 is slidably positioned. The valve gate 28 is substantially cylindrical in cross section and terminates in a finger 29 at its upper end. The lower end of the valve gate 28 carries a yoke 30 which opens downwardly. A recess 31 is also provided in a portion of the bonnet 2, the recess 31 being in communication and in substantial axial alignment with the recess 27. A movable valve seat 32 is positioned in the recess 31. The arrangement is such that the tube 12 where it passes through the passageway 10, is disposed between finger 29 of the valve gate 28 and valve seat 32. As will be hereinafter more fully described, by moving the valve gate 28 toward or away from the valve seat 32 the tube 12 may be relatively squeezed or relatively released.

A fulcrum pin 33 is threadedly positioned in the lower face of the partition 8, the end of said pin being engaged in a recess 34 provided adjacent one end of lever 35. An intermediate portion of the lever 35 is pivotally connected to the lower end of the connecting rod 20, as at 36 in Fig. 1, and the opposite end of the lever 35 carries an abutment screw 37 which is positioned within the yoke 30.

In operation, the device comprising the present invention may be connected in a piping circuit (not shown) through which a fluid carrying abrasive material may pass. The connections are so made that the abrasive carrying material passes inwardly through the inlet boss 6 and passes outwardly through the outlet boss 7. The screw 24 may be adjusted to cause plate 17 to exert a predetermined downward pressure upon the coiled tubing 12. In compressing the coiled tubing the connecting rod 20 is moved axially downwardly. Such movement is transmitted to lever 35 which in turn lowers the valve gate 28. In lowering the valve gate 28 the pressure exerted by the finger 29 of the valve gate against the tubing is released and the cross sectional area of the tubing between the valve gate and the valve seat 32 is increased. In increasing this cross-sectional area a greater pressure is established within the coiled tubing 12 and hence said tubing 10 tends to distend. In distending, the control plate

17 tends to raise. This movement tends to move the valve gate 28 upwardly within the recess 27 and the pressure of the finger 29 upon the tubing in said recess tends to decrease the cross-sectional area of the tubing. In this fashion an equilibrium is established and the position of the control plate 17 and valve gate 28 eventually becomes fixed with a predetermined setting of the compression upon the coil spring 22.

It can readily be seen, that for each predetermined setting of the compression of the coil spring 22 a different equilibrium position will be established between the control plate 17 and valve gate 28 and hence the device may be set to permit desired rates of flow of the material passing in the circuit. It can also be seen that with a predetermined setting of the compression of the coil spring 22 the rate of flow and, hence, the pressure of the fluid passing through the tubing 12 will be maintained constant.

Valve seat 32 is carried upon a rod 38 which is slidably positioned in an aperture provided in bonnet 2. A pin 39 is transversely positioned upon rod 38 within recess 31 and the upper portion of said recess is provided with a groove 40 into which the transverse pin 39 may register when rod 38 is rotated to a predetermined position. For instance, in Fig. 1, pin 39 is illustrated as being at right-angles to groove 40 and, hence, rod 38 is disposed in its lowermost position. In this position of rod 38, the valve seat 32 is in its operative position to serve as an abutment against which tube 12 may be pressed by valve gate 28. A knob 41 is carried upon the upper protruding end of rod 38, by means of which, rod 38 may be rotated to the position illustrated in Fig. 3. In this position the pressure within tube 12 will move rod 38 upwardly, such movement being accommodated by the registration of pin 39 in groove 40. When rod 38 is in this position, gate 28 is substantially ineffective in controlling the flow through the tube. The movable seat 32 thus provides a convenient pressure release which may be quickly manipulated if occasion demands.

The screw 37 carried at the end portion of lever 35 is employed primarily as a calibrating means. When no fluid under pressure is contained within tube 12, the compression of spring 22 is sustained entirely by the resiliency of tube 12. Hence, lever 35 will be depressed to a predetermined position at which the tube 12, where it passes between finger 29 and valve seat 32 should be closed. By the adjustment of screw 37 this closed condition of tube 12 may be secured. Thereafter, when fluid under pressure is introduced into the tube, said tube, between finger 29 and valve seat 32, distends and the equilibrium condition, hereinbefore described obtains which is dependent upon the adjustment of spring 22.

It is apparent that other forms of the invention may be made by any one skilled in the art without departing from the essential principles of the invention and, hence we do not wish to be limited to the specific structure shown and described except as necessitated by the appended claims.

We claim as our invention:

1. A fluid regulator comprising in combination, a rela-

tively flat support, a spirally coiled resilient distendible tube having a plurality of convolutions carried by said support and adapted for connection in a fluid flow circuit, a relatively flat plate positioned upon said coiled tube to substantially cover all of said convolutions, resilient means for urging said plate into contact with said tube and acting against said support whereby said plate is responsive to distention of said tube due to fluid pressure therein, a valve gate for controlling the flow of fluid through said tube, means connecting said plate and said valve gate to actuate said valve gate to control the fluid flow through said tube in response to the degree of distention of said tube, and means carried by said connecting means for completely closing said valve gate.

2. A fluid regulator comprising in combination, a body, a support in said body, a resilient, distendible tube carried upon said support and adapted for connection in a fluid flow circuit, a plate positioned upon said tube upon said support, adjustable spring means for resiliently maintaining said plate in contact with said tube for resisting distention of said tube due to fluid pressure therein, a valve gate for squeezing said tube to control the flow of fluid through said tube, and lever means connecting said plate and said valve gate to cause said valve gate to squeeze said tube to control the fluid flow through said tube in response to the degree of distention of said tube, said lever means comprising a rod carried by said plate and extending through said support, a lever pivotally mounted upon said support, means pivotally connecting said rod to an intermediate portion of said lever, and adjustable contact means upon the free end of said lever for actuating said valve gate.

3. A fluid regulator comprising in combination, a housing, a spirally coiled resilient distendible tube positioned in said housing, an inlet for said tube and outlet for said tube carried by said housing for connection in a fluid circuit, spring-impelled means carried in said housing in contact with said coiled tube for resisting distentions of said tube due to fluid pressure therein, a valve gate carried by said housing and in contact with said tube for controlling the flow of fluid through said tube, a connecting rod carried by said spring-impelled means, a lever pivoted at one end in said housing the opposite end thereof being in actuating relationship to said valve gate, and means for pivotally securing said connecting rod to said lever for rocking said lever in response to distention of said tube.
